UNITED STATES PATENT OFFICE.

JOHN TOLER, OF NEWARK, NEW JERSEY.

FURNITURE-CASTER.

SPECIFICATION forming part of Letters Patent No. 224,249, dated February 3, 1880.

Application filed October 9, 1879.

To all whom it may concern:

Be it known that I, JOHN TOLER, of Newark, in the county of Essex and State of New Jersey, have invented a new and Improved Caster, of which the following is a specification.

The object of my invention is to provide a solid bearing in a two-part caster-socket for the conical head of the caster-spindle, and to secure the spindle in said two-part socket without the use of screws or rivets.

In the accompanying drawings, Figure 1 is a bottom view of my improved caster in position in the table-leg. Fig. 2 is a sectional elevation of the same, taken on line $x-x$ of Fig. 1, at right angles to the line of division of the socket. Fig. 3 is a sectional elevation of the caster and table-leg, taken on line $y-y$ of Fig. 1, in the line of the division of the socket; and Fig. 4 is an elevation of the caster and its spindle, the latter being in the part of the socket containing the bearing.

Similar letters of reference indicate corresponding parts.

Referring to the drawings, A is the leg of a table, provided with a hole or socket, a, for the reception of the metal socket of the caster. The metal caster-socket is composed of two semi-cylindrical parts, b b'. Part b is a plain semi-cylindrical piece of metal, with a flange, c, on its lower end to bear against the end d of the leg A, and having on its outside, near its end e, a spur, f, to take hold of the side of socket a. Part b' is of the same shape as part b, but on its upper end, e', is a head-piece, f', the rounded edge f'' whereof projects beyond the edges g g of part b', so that when parts b b' are put together edge to edge the rounded edge f'' fits against the concave inside walls of part b at the upper end, e, as shown in Fig. 2, and thus forms a head for the cylindrical socket. Inside of part b' is cast a collar, h, at such a point as to leave sufficient space between it and the concave surface i of head f' for the conical head j of the caster-spindle B. In the flange k of part b' is a semicircular

notch, l. C is a metal ferrule placed around the leg A, to prevent it from splitting.

The manner of applying the invention is as follows: Part b is first inserted in socket a on one side of said socket, and with its flange c against the end d of the leg A. The spindle B is then placed in part b', with its head j between collar h and head f'. While held in this position the end e' of part b' is inserted in socket a, (the edges g g of part b' must be placed next to the corresponding edges of part b.) The part b' is now forced in socket a until its flange k bears against the end d of leg A. The pressure of part b' in passing into the socket against part b forces the latter against the side of socket a and the spur f into said side, as shown in Fig. 2. A nail, l', or screw is now driven through notch l into the end d of leg A. The spur f and nail l', respectively, hold the parts b b' in socket a, and the collar h holds the spindle B in the metal socket formed by parts b b', while the head f' furnishes a solid bearing for the point of the spindle-head j.

Having thus described my invention, what I claim as new, and desire to secure by Letters Patent, is—

1. In a caster-socket consisting of two parts, b b', the spur f, arranged on the outside and near the upper end of the part b, as and for the purpose described.

2. The combination, with a caster-spindle having conical head j and a leg having the hole a, of the socket made in two parts, b b', the part b being semi-cylindrical, having flange c at its lower end, a spur, f, at its upper end, and concaved inside walls at end e, and the part b' having concave head-piece f' i, with rounded edge f'', collar h, and flange k, having semicircular notch l, all substantially as shown and described.

JOHN TOLER.
